UNITED STATES PATENT OFFICE.

JAMES TAYLOR, JR., OF WORCESTER, MASSACHUSETTS.

INSTRUMENT FOR EAR TREATMENT.

Application filed April 8, 1920. Serial No. 372,196.

To all whom it may concern:

Be it known that I, JAMES TAYLOR, Jr., a citizen of the United States, residing at Worcester, in the county of Worcester and 5 Commonwealth of Massachusetts, have invented a new and useful Improvement in an Instrument for Ear Treatment, of which the following, together with the accompanying drawings, is a specification.

10 My invention relates to an instrument particularly adapted for aural treatment and embodying means for aural inflation through the nostrils and connected passages, and it has for its object to provide an instrument 15 by means of which aural inflation can be accomplished with a minimum inconvenience to the patient, or by the patient himself, and by which a desirable moisture is applied to the passages leading to the ear.

20 Aural inflation has been heretofore practiced by the use of a catheter, which is a painful method, and obviously not adapted for the treatment of children, or by what is known as the Politzer method, or by one 25 of its various modifications, requiring co-operation on the part of the patient, either by the act of swallowing, or by the pronunciation of certain sounds which close the upper region of the pharynx by the palate.

30 By my present invention I provide an effective instrument for aural inflation which can be accomplished by the patient himself in chronic cases, at his own convenience, and enable the aurist to witness the massage of 35 the middle ear and its annexes by inspection, a great advantage in otological diagnosis.

These objects among others I accomplish by an instrument hereinafter described and illustrated in the accompanying drawings, 40 in which

Figure 1 represents the instrument with its operating bulb attached.

Figure 2 is a central sectional view, showing the inclosed chambers and connecting 45 passages, and illustrating the details of construction.

Referring to the drawings the instrument comprises a mixing chamber 1 and a delivery chamber 2 connected by a screw threaded 50 tube 3. The chambers 1 and 2 are preferably flared at their outer ends to receive the screw threaded tubes 4 and 5 communicating with the mixing chamber 1, and the screw threaded tubes 6 and 7 communicating with 55 the delivery chamber 2. Screwed upon the tubes 6 and 7 are metal bulbs 8 and 9 adapted

to fit and close the nostrils of the patient. The tub 4 is provided at its outer end with an annular recess 10 to receive a rubber tube 11 connected with a rubber compression bulb 12 having in its end an air valve 13 of the usual type in compression bulbs of this class, admitting air to the bulb but preventing its discharge. The tube 5 is enlarged at its outer end to form a reservoir 14 for any 60 suitable germicidal volatile preparation, having its exterior screw threaded at 15 to receive an internally threaded sleeve 16 having its outer end closed at 17.

When it is desired to use the instrument, 70 the reservoir 14 is first filled with a volatile and germicide solution, preferably applied through the nasal bulbs 8 and 9, thus moistening the tubes 6 and 7 and air chambers 1 and 2. When the bulb 12 is compressed, 75 air is forced into the mixing chamber 1 where it mixes with the solution carrying some of it through the nostrils and connected passages into the middle ear. The chambers 1 and 2 thoroughly mix the solution 80 and air current without sending a spray through the bulbs 8 and 9.

The tubes 6 and 7 are so shaped that the bulbs 8 and 9 will hug the nasal septum and the bulbs 8 and 9 of sufficient size to fill 85 the nostrils, thereby completely closing the nostrils to the admission of air except as it is forced through the perforations of the bulbs. This is an important feature of my present invention and distinguishes it from 90 similar apparatus designed for the administration of anesthetics, and enables the withdrawal of pus or the active massage of the middle ear and connected passages, as hereinafter described. The patient is then instructed to first breathe in deeply and then 95

to inflate the cheeks, with the lips tightly closed so that no air escapes. The patient may try this a few times, with the aurist testing the pressure of the inflated cheeks to 100 insure that no air is escaping from the mouth. The instrument is then applied to the nasal orifices and the bulb 12 is compressed. The air enters the mixing chamber where it takes up a certain amount of moisture from the solution, as described before, and then passes on through the tubes 6 and 7, to the nasal passages where it deposits the solution carried by the air current.

105 It is obvious that the compression of the bulb condenses the air in the aural passages and that the air will be rarified upon the 110

release of pressure on the bulb. In this way, by alternately compressing and releasing the bulb, a massage of the middle ear, eustachian tube, nasal pharynx, and other nasal 5 passages can be obtained. In addition, suction can be induced in the aural passages by using the instrument with the bulb compressed before applying it to the nasal orifices, and then slowly releasing the bulb, 10 thus causing traction of the passages, so that any secretion can be thus drawn from the middle ear and other passages and even a bulging ear drum reduced. In addition, the inventive aurist can find many other uses for 15 the instrument in the treatment of turbinates, antrums, frontal sinuses, etc.

The use of the instrument is attended with no detrimental results to the aural and nasal passages, inasmuch as a germicide solution 20 is always carried in with the air from the bulb. The passages are also kept moistened during the treatment by the solution; and this result is believed to be of considerable importance, for the reason that in the 25 absence of the solution, movement of the air alone through the passages would tend to dry them out, which would be undesirable.

By means of the screw threaded connections 30 the separate parts of the instrument itself can be readily disassembled for cleaning, and sterilization. As the germicide solution is gradually withdrawn from the reservoir 14, the sleeve 16 is screwed upon the reservoir to force a fresh supply into the 35 mixing chamber.

The germicide solution is wholly within the control of the operator and is forced di-

rectly into the chamber 1 by screwing up the sleeve 16. From the chamber 1, the solution is taken up by the air current through 40 the tube 4, thereby impregnating the air current without producing a spray. And as the nasal tubes 6 and 7 are connected directly with the mixing chamber 2, no spray is produced at the discharge end of these 45 tubes, but instead a simple pressure of air impregnated with the solution is forced into one of the chambers.

I claim:

1. In an apparatus of the class described, 50 the combination of a pair of chambers having a connecting tubular passage between them, a reservoir for a germicidal solution communicating with one of said chambers, screw threaded means for forcing the solution from said reservoir into one of said chambers, and means for forcing a current of air through both of said chambers.

2. In apparatus of the class described, a 55 chamber having a pair of nasal tubes leading therefrom and providing opposed divergent and convergent portions, each convergent tube portion terminating in a conical nasal bulb having a passage therethrough coaxial with its associated tube portion, 60 whereby opposed surfaces of said bulbs are maintained substantially parallel and are adapted to press evenly against the nasal septum when inserted in the nostrils. 65

JAMES TAYLOR, JR.

RUFUS B. FOWLER,
NELLIE WHALEN.

Certificate of Correction.

It is hereby certified that in Letters Patent No. 1,533,618, granted April 14, 1925, upon the application of James Taylor, jr., of Worcester, Massachusetts, for an improvement in "Instruments for Ear Treatment," errors appear in the printed specification requiring correction as follows: Page 1, line 58, for the word "tub" read *tube*; same page, line 85, after the numeral "9" insert the word *are*; page 2, beginning with line 59, strike out present claim 2, and insert the following as claim 2:

2. In an apparatus of the class described, a pair of chambers, a tubular passage connecting said chambers and attached thereto by screw threaded joints, a pair of nasal tubes having a screw threaded connection with one of said chambers, and a second pair of tubes having a screw threaded connection with the other of said chambers, with one of said second pair of tubes leading to a compressible reservoir, and the other of said second pair of tubes leading to an apparatus for forcing air through said chambers.;

and that the said Letters Patent should be read with these corrections therein that the same may conform to the record of the case in the Patent Office.

Signed and sealed this 12th day of May, A. D. 1925.

[SEAL.]

KARL FENNING,
Acting Commissioner of Patents.
